UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

FEEDING MECHANISM FOR SEWING-MACHINES.

1,209,609.

Specification of Letters Patent. Patented Dec. 19, 1916.

Application filed January 4, 1912. Serial No. 669,377.

To all whom it may concern:

Be it known that I, JAMES R. MOFFATT, a citizen of the United States, residing at Chicago, in the county of Cook, State of Illinois, have invented certain new and useful Improvements in Feeding Mechanisms for Sewing-Machines, of which the following is a description, reference being had to the accompanying drawing and to the letters and figures of reference marked thereon.

My invention relates to an improvement in sewing machines, and more especially to the feeding mechanism therefor.

The object of the invention is to provide a differential feeding mechanism for a "feed up the arm" sewing machine, of which the type is illustrated in Patent No. 583,415, of May 25th, 1897. Reference is made to said patent for a general understanding of the construction and arrangement of the parts of the machine, although it will be understood that the present construction of feeding mechanism might be used on other types of machines.

The invention therefore consists in the matters hereinafter described and referred to in the appended claims.

In the accompanying drawings which illustrate the invention; Figure 1 is a side elevation, partly in section, of a sewing machine embodying my invention; Fig. 2 is a plan view with the top of the bed plate and the parts above said bed plate, removed, but leaving the throat plate attached to the cylindrical casing; Fig. 3 is a side elevation of Fig. 2, the bed plate or casing being removed, except as to its forward part, the feed dogs being shown in their elevated and feeding position; Fig. 4 is a view similar to Fig. 3, the feed dog being shown in lowered position, the dotted lines illustrating the parts in a different position from that shown in full lines; Fig. 5 is a detail view of the parts of the auxiliary feed mechanism;

Fig. 6 is a detail view of the parts of the main feed mechanism; Figs. 7 and 8 are respectively side views showing the feed dogs in different operative relations; Fig. 9 is a detail view of the lever for adjusting the movement of the auxiliary feed dog; Fig. 10 is a detail view of the connection between the feed operating cross shaft, and the slotted segment; Fig. 11 is a detail view of said slotted segment; Fig. 12 is a view of the connecting parts shown in Fig. 10, with the

slotted segment or bell crank shown in Fig. 11; Fig. 13 is a bottom plan of the throat plate; and Fig. 14 is a section, showing also the feed dog frame.

In these drawings, the machine is of the type above referred to, except that it has in addition thereto, vibrating thread-carrying fingers which lay threads back and forth across the line of the seam, the same being secured to the fabric by the threads of three needles, with which needles concatenates on the under side of the fabric, a single thread carried by a looper supported on the usual looper shaft. This machine is well known in the art as the Union Special side wheel triple interlock machine, and as to its details need not be especially referred to, reference being had to the aforesaid patent.

In these drawings, 1 represents the usual standard of a machine of the type indicated, which has a transverse shaft operating the various mechanisms carried within the cylindrical casing or work supporting arm

2. The gooseneck or overhanging arm is represented by 3, the needle bar by 4, here-in shown as carrying three needles 5, the presser bar is shown at 6, the presser foot at 7, and the thread-carrying fingers which lay a thread back and forth across the line of feed to be held in place by the needle threads, at 8. The looper shaft is shown at 9, the feed bar at 10, and the feed reciprocating lever at 11, these parts being operated from the main transverse shaft 12, above mentioned.

The looper shaft 9 carries at its outer end outside of the outer wall, of the casing a head 13 provided with an opening 14, for the reception of the looper shank. The looper in this machine has all its movements outside of the outer wall of the casing, and beneath the main feed dog and supplemental feed dog, both of which are also outside of the outer end of the casing. Said outer end of the casing is covered by the usual end cap 15. The feed bar 10 is pivoted in the usual way in the casing at 16, and at its outer end has links 17 which straddle the looper shaft, and at their upper ends, are attached to a part of the feed mechanism in order to give the same its up and down movements.

The feed reciprocating lever 11 is operated from the main shaft, and is pivoted to the cross shaft 18, which has the upwardly

projecting parts 19 and 20, the latter of which is formed with a slot 21, in which is adjustably pivoted one end of the arm 22, attached at its other end to the bar 23 shown 5 in detail in Fig. 6. This bar 23 at its rear end, is split as at 24, the split portion embracing the pin 25 extending between the two upright parts 19 and 20. To the opposite end of this bar 23 is adjustably secured 10 the main feed rod 26, to which at its outer end, is secured by a screw the head 27 carrying the side and intermediate portions of the main feed dog 28. The bar 23 has a split sleeve at its end, which receives the rod 15 26 and a screw 28 clamps the parts together. Except for the exact construction of the main feed rod, the main feed dog and the part 19, these elements are all substantially of the construction illustrated in the afore- 20 said patent.

The part 19 has attached to it the arm 29 which surrounds the cross shaft 18, and at its forward end is pivoted to the vertical link 30 which at its upper end is pivoted to 25 the bell crank lever 31 having pivotal connection at 32 with the bar 23. One arm of this bell crank lever is provided with a slot 33, in which is adjustably secured one end of the lever 34 secured at 35 to the rear part 30 36 of the auxiliary feed frame. This lever 34 has a hand piece 37 by means of which it may be manipulated to adjust the rear end of said lever 34 up and down in the slot 33, to vary the amount of reciprocation of said 35 lever 34. The auxiliary feed frame is composed of the rear part 36 and the forward part 38, which respectively have central openings 39 for the passage of the main feed bar 26. These two parts 36 and 38 40 are connected by a bar 40 formed of two parts adjustable one on the other. The bar 40 is pinned at each end between projections 41 on each block 36 and 38. Below the bar 40, a trough-shaped block 42 engages the 45 main feed bar, this block being connected to the link 17 hereinbefore referred to. The forward block 38 has integrally formed with it the feed dog frame having the side bars 43 at the forward end of which are formed 50 the side feed dogs 44, and between the two, a broad feed dog 45.

In the oscillation of the cross shaft 18, the main feed rod 26 and the main feed dog 28 carried thereby are reciprocated in the 55 manner set forth in the aforesaid patent. At the same time, motion is transmitted through the member 29, link 30, bell crank lever 31, and lever 34, to the auxiliary feed frame which reciprocates back and forth 60 upon the main feed rod 26. By this means, and according to the position of the end of the lever 34 in the slot 33, a differential movement of the auxiliary feed dog with respect to the main feed dog is given, thus 65 giving the usual desirable action attendant

upon a differential feed in the sewing of fabrics, particularly knit goods, in which it is desired to gather the goods slightly ahead of the needles.

As shown in Figs. 13 and 14 the underside of the throat plate is cut out or recessed as at 46 to house the side bars 43 of the auxiliary feed dog. By the pivotal connection of the bell crank lever 31 with the bar 23, the former has not only an oscillating movement on its pivot to reciprocate the supplemental feed dog, but a bodily reciprocating movement, and thereby the differential movement is compounded. Furthermore, the making of the bar 40 in two parts adjustable one on the other provides an additional adjustment for the auxiliary feed. This is desirable in the assembling of the machine to make the feed dog conform to the slots in the throat plate, and also to 35 make one feed conform to another. The main feed dog bar is carried through the center of the block 38, and the latter bears on the sides of the guiding slot formed by milling out the outer end of the casing. 90

It will be understood that I do not wish to be limited to the exact details of construction and operation of the auxiliary feeding mechanism, but many modifications and changes may be made without departing from the spirit of my invention. 95

Having thus particularly described my invention, what I claim as new and desire to secure by Letters Patent is:—

1. A machine having a work supporting 100 arm, a looper support arranged longitudinally thereof, a feeding mechanism also arranged longitudinally thereof, including a reciprocating feed dog carrying bar, and a supplemental feed dog carrying frame supported by and reciprocating longitudinally relative to said feed dog carrying bar. 105

2. A machine having a work supporting arm, a looper shaft arranged longitudinally thereof, a feeding mechanism also arranged 110 longitudinally thereof, including a reciprocating feed dog carrying bar, a supplemental feed dog carrying frame supported by and reciprocating longitudinally relative to said feed carrying bar, both of said feed dogs projecting beyond the end of the work supporting arm, and the looper support on the end of the looper shaft being beneath the same. 115

3. A machine having a work supporting 120 arm, a looper shaft arranged longitudinally thereof, a feeding mechanism also arranged longitudinally thereof, including a reciprocating feed dog carrying bar, a supplemental feed dog carrying frame supported by and reciprocating longitudinally relative to said feed dog carrying bar, and means for adjusting 125 the movements of the feed bar and feed frame.

4. In combination with a main feed bar, a 130

supplemental feed frame composed of two parts surrounding the main feed bar adjacent its ends and movable thereon, an intermediate bar connecting the two parts and a supporting bearing for said main feed bar between the parts of the supplemental feed frame.

5. In combination with a main feed bar, a supplemental feed frame composed of two parts surrounding the main feed bar adjacent its ends and movable thereon, and an intermediate bar pivoted to both of said parts.

15 6. In combination with a main feed bar, a supplemental feed frame composed of two parts surrounding the main feed bar adjacent its ends and movable thereon, an intermediate bar pivoted to both of said parts, a block below the intermediate bar supporting
20 the main feed bar, and means connected to said block for raising and lowering the feed bar and feed frame.

7. A feeding mechanism including a sliding main feed bar, a differential feed frame supported on both ends of said bar and slideable thereon, the forward end of said feed frame being provided with an open feed dog frame, and the main frame being provided with a feed dog contained within said feed dog frame.

8. A feeding mechanism including a sliding main feed bar, a differential feed frame supported on both ends of said bar and slideable thereon, the forward end of said feed frame being formed with an integral open feed dog frame, and the main feed dog being provided with a feed dog inclosed by said feed dog frame.

9. In a sewing machine having a work supporting arm, a feeding mechanism arranged longitudinally thereof to feed the goods longitudinally of said work supporting arm, said feeding mechanism including a main feed dog reciprocating bar, and a supplemental feed dog carrying frame supported by the main feed dog bar, with means for imparting to the frame a differential movement relative to the bar.

10. In a sewing machine having a work supporting arm, a feeding mechanism arranged longitudinally thereof to feed the goods longitudinally of said work supporting arm, said feeding mechanism including a main feed dog reciprocating bar, and a supplemental feed dog carrying frame supported by the main feed dog supporting bar, with means for imparting to the frame a differential movement relative to the bar, and means for independently adjusting the movement of each of the feed dog carrying members.

11. In a sewing machine having a work supporting arm, a feeding mechanism arranged longitudinally thereof, to feed the goods longitudinally of said work support-
65

ing arm, said feeding mechanism including a main feed dog reciprocating bar, a supplemental feed dog carrying frame supported by the main feed dog supporting bar, with means for imparting to the frame a differential movement relative to the bar, said supplemental feed dog carrying frame inclosing the main feed dog reciprocating bar, and means for raising and lowering them in unison. 70

12. In a sewing machine in combination with a main feed bar, a supplemental feed mechanism, including a pivoted lever attached to the main feed bar, means for oscillating said lever, and a lever adjustably secured at one end to said pivoted lever and attached to the supplemental feed mechanism, said lever having a projecting hand piece.

13. The herein described feeding mechanism comprising the main feed bar, and an auxiliary feeding mechanism including an auxiliary frame, an oscillating means, a bell crank lever pivoted to the main feed bar, and having one arm connected to said oscillating means, the other arm being provided with a slot, and a lever pivoted at one end to the auxiliary frame, and at the other end adjustably secured in said slot. 14. A feeding hand piece.

14. In a feeding mechanism, a main feed bar, a supplemental feed bar, a rocking frame, a second rocking frame movable bodily by the first rocking frame and having an independent connection with the first rocking frame whereby the oscillations of the first rocking frame are imparted to said second rocking frame, and connections between the first rocking frame and the main feed bar and connections with the second rocking frame and the supplemental feed bar for moving said feed bars longitudinally; 95 100 105

15. A sewing machine including in combination, a standard, a horizontal work supporting arm carried by and projecting from said standard, a feeding mechanism comprising a main feed bar extending longitudinally of and located within said work supporting arm, a main feed dog carried thereby, means for raising and lowering said main feed bar means for moving said main feed bar back and forth, an auxiliary feed dog carrying support carried by and reciprocating longitudinally relative to the main feed bar and movable up and down with said main feed bar, an auxiliary feed dog carried by said auxiliary feed dog carrying support and means for moving said auxiliary feed dog carrying support back and forth, including devices located within said work supporting arm. 110 115 120 125

16. A sewing machine including in combination, a standard, a horizontally disposed work supporting arm carried by and projecting from said standard, a main feed dog and an auxiliary feed dog operating at 130

- the free end of said work supporting arm, a main feed bar supporting said main feed dog and located within and extending longitudinally of the work supporting arm, an auxiliary feed bar supporting said auxiliary feed dog and located within said work supporting arm and extending longitudinally thereof, means for operating said feed bars including devices interposed between the feed bars and located in said horizontally extending work supporting arm for giving one of said feed bars a differential movement relative to the other.
17. A sewing machine including in combination, a standard, a driving shaft supported by and extending transversely of the standard, a horizontal work supporting arm carried by the standard and projecting at right angles to the longitudinal axis of the transverse shaft, independent feed dogs located at the free end of the arm, feed bars for the respective dogs disposed within the work supporting arm and extending longitudinally of said work supporting arm and mechanism actuated by said transverse shaft for operating the feed bars, said mechanism including devices for giving one of said feed bars a differential movement relative to the other feed bar.
18. A sewing machine including in combination, a standard, a driving shaft supported by and extending transversely of the standard, a horizontal work supporting arm carried by the standard and projecting at right angles to the longitudinal axis of the transverse shaft, independent feed dogs located at the free end of the arm, feed bars for the respective dogs disposed within the work supporting arm and mechanism actuated by said transverse shaft for operating said feed bars, said mechanism includ-

ing devices located within the work supporting arm for giving one of said feed bars a differential movement relative to the other feed bar.

45

19. In a sewing machine, a differential feeding mechanism, a work supporting arm having a guiding slot, a main and a supplemental feed bar and said supplemental feed bar being carried on said main feed bar and having the sides of the supplemental feed bar in engagement with the guiding slot.

50

20. In a feeding mechanism, a main and a supplemental feed dog, said supplemental feed dog having side bars extending from front to back and in a plane outside of its feeding tooth, the throat plate having a cut-away portion upon its under side for housing the side bars of the supplemental feed dog.

60

21. In combination with a main feed bar, a supplemental feed frame composed of two parts surrounding the main feed bar adjacent its ends and movable thereon, an adjustable intermediate bar pivoted to both of said parts, a block below the intermediate bar supporting the main feed bar, and means connected to said block for raising and lowering the feed bar and feed frame.

65

22. In combination with the main feed bar, a supplemental feed frame composed of end parts sliding on said feed bar, connected by an intermediate adjustable bar and a support for said main feed bar between the parts of the supplemental feed frame.

70

In testimony whereof I affix my signature, in presence of two witnesses.

JAMES R. MOFFATT.
